US00D712154S

(12) **United States Design Patent**
Schiller et al.

(10) **Patent No.:** US D712,154 S
(45) **Date of Patent:** ** Sep. 2, 2014

(54) **TAG-LOOP CARRIER ASSEMBLY**

(71) Applicant: **Bedford Industries, Inc.**, Worthington, MN (US)

(72) Inventors: **David Schiller**, Sioux Falls, SD (US); **Curtis John Heinrichs**, Sibley, IA (US)

(73) Assignee: **Bedford Industries, Inc.**, Worthington, MN (US)

(**) Term: **14 Years**

(21) Appl. No.: **29/437,913**

(22) Filed: **Nov. 21, 2012**

(51) LOC (10) Cl. **03-01**

(52) U.S. Cl.

USPC **D3/328**

(58) **Field of Classification Search**

USPC D3/318, 328

See application file for complete search history.

(57) **CLAIM**

The ornamental design for a tag-loop carrier assembly, as shown and described.

DESCRIPTION

FIG. 1 is a front view of a first embodiment thereof;
FIG. 2 is a back view thereof;
FIG. 3 is a top view thereof;
FIG. 4 is a bottom view thereof;
FIG. 5 is a side view thereof, as taken from the left side of FIG. 1;
FIG. 6 is a side view thereof; as taken from the right side of FIG. 1;
FIG. 7 is a sectional view as taken along lines 7-7 in FIG. 1;
FIG. 8 is a front view of a second embodiment thereof;
FIG. 9 is a back view thereof;
FIG. 10 is a top view thereof;
FIG. 11 is a bottom view thereof;
FIG. 12 is a side view thereof, as taken from the left side of FIG. 8;
FIG. 13 is a side view thereof; as taken from the right side of FIG. 8;
FIG. 14 is a sectional view as taken along lines 14-14 in FIG. 8;
FIG. 15 is a front view of a third embodiment thereof;
FIG. 16 is a back view thereof;
FIG. 17 is a top view thereof;
FIG. 18 is a bottom view thereof;
FIG. 19 is a side view thereof, as taken from the left side of FIG. 15;
FIG. 20 is a side view thereof; as taken from the right side of FIG. 15; and,
FIG. 21 is a sectional view as taken along lines 21-21 in FIG. 15.

The evenly spaced broken lines showing portions of the tag loop are for the purposes of illustrating environment. The dot-dashed lines illustrate the boundaries of the claim. Neither of the broken lines are part of the claimed design.
